BOOM ATTACHMENT FOR LIFT TRUCKS FOR
LOADING NARROW-DOOR BOXCARS

Jesse C. Fowler, Box 222, Williams, Ariz.

Filed Dec. 12, 1958, Ser. No. 780,116

6 Claims. (Cl. 214—620)

This invention relates to loading attachments for industrial lift trucks, and more particularly to a boom attachment for a fork lift truck especially adapted for use in loading narrow single-door box cars.

A main object of the invention is to provide a novel and improved boom attachment for a fork lift truck, said attachment being simple in construction, being easy to mount on a fork lift truck, and providing a great saving in time and labor in the handling of packaged loads, such as stacks of lumber, or the like.

A further object of the invention is to provide an improved boom attachment for a standard industrial fork lift truck, said attachment involving inexpensive components, being durable in construction, and being safe to use.

A still further object of the invention is to provide an improved boom attachment for a fork lift truck, said attachment being adjustable in accordance with the size of the load to be handled, being smooth in operation, and greatly reducing the amount of human effort required in loading bundles of lumber or similar packaged objects into freight cars of the type having relatively narrow doors.

Further objects and advantages of the invention will become apparent from the following description and claims, and from the accompanying drawings, wherein:

Figure 1 is a perspective view of an improved boom attachment for a fork lift truck constructed in accordance with the present invention, showing the manner in which the attachment is used for handling a bundle of boards.

Figure 2 is a side elevational view of a boom attachment according to the present invention shown operatively engaged with a fork lift truck and illustrating the manner in which a load is elevated for placement in a box car.

Figure 3 is a top plan view of the structure shown in Figure 2.

Figure 4 is an enlarged vertical cross sectional view taken on the line 4—4 of Figure 3.

Figure 5 is a horizontal cross sectional view taken on the line 5—5 of Figure 4.

Figure 6 is an enlarged fragmentary vertical cross sectional view taken on the line 6—6 of Figure 2.

Figure 7 is a perspective view of the load carrier member employed in the boom attachment of Figures 1 to 6, shown with its fastening straps disengaged from the main body portion of the carrier assembly.

Referring to the drawings, the improved boom attachment is designated generally at 11 and comprises a generally rectangular base plate 12 of heavy rigid material, such as sheet steel of substantial thickness. Rigidly secured to the underside of the plate 12 adjacent its side margins are the respective longitudinally extending channel bars 13 and 14, said channel bars being spaced to receive the respective fork elements 15 and 16 of a standard fork lift truck, designated generally at 17 and shown fragmentarily in Figures 2 and 3.

2

Designated generally at 19 is an upstanding bracket structure mounted on the rear portion of the base plate 12, said bracket structure comprising a transversely extending upstanding vertical main bracket plate 20 braced and supported by a pair of generally triangular forwardly divergent gusset plates 21, 21 which are welded at their bottom edges to the top surfaces of the base plate 12 and which are welded at their rear edges to the vertical side edges of the transverse vertical bracket plate 20.

As shown in Figures 1 and 4, the transversely extending upstanding vertical bracket plate 20 is located at the transverse rear edge of the main plate 12 and depends below said main plate, defining a depending transverse flange element to which the rear ends of the sleeve members 13 and 14 may be welded. A transversely extending bottom channel member 24 is welded to the underside of the main plate 12 and to the inside flanges of the sleeve channels 13 and 14, as well as to the depending portion of the vertical transverse bracket plate 20, as shown in Figure 4.

Rigidly secured to the bracket plate 20 are the vertically spaced, rearwardly extending pivot lugs 25 and 26, the pivot lug 25 being secured, as by welding, or the like, to the bottom marginal portion of the plate 20 and the pivot lug 26 being secured to the upper portion of said bracket plate in vertical alignment with the bottom lug 25.

Designated at 27 is a first tubular, horizontally extending boom member which is rigidly secured at its end to a transversely extending support plate 28 which depends a substantial distance below the tubular boom member 27, as is clearly shown in Figure 4. Generally triangular vertical side plates 29, 29' are provided at the opposite sides of the tubular boom member 27, said side plates being welded to the boom member 27 at their top margins and being welded to the plate member 28 at their vertical edges, whereby to define a rigid and securely braced connection of the boom member 27 to the plate member 28. Respective horizontal pivot lugs 29 and 30 are welded to the forward surface of the plate member 28, the lower lug 29 overlying the bottom pivot lug 25 associated with the base plate 12 and the upper pivot lug 30 overlying the upper pivot lug 26 associated with said base plate. Suitable bearing bushings 31' and 30' are provided between the respective pivot lugs 30, 26 and 29, 25, as shown in Figure 4.

A vertical pivot pin 31, headed at its top end, is engaged through the respective pairs of pivot lugs, as is clearly shown in Figure 4, providing a vertical hinge connection between the tubular boom member 27 and the rear end portion of the base plate 12.

Rigidly secured to the outer surfaces of the triangular base plates 29, 29' are respective horizontal flange plates 32, 32', said horizontal flange plates extending beyond the transverse plate member 28 toward the bracket plate member 20, and disposed intermediate the respective pairs of pivot lugs 30, 26 and 29, 25. The horizontal flange plates 32 have transverse edges 33 which are spaced from the vertical transverse bracket plate 20 by a sufficient distance to normally allow the boom member 27 to swing to a relatively wide angle, for example to a position such as that shown in dotted view in Figure 5. However, when it is desired to prevent such swinging, a transverse stop bar 38 is engaged between the edges 33 of the flange plates 32, 32' and the transversely extending upstanding vertical bracket plate 20, said stop bar 34 being supported on a transversely extending horizontal shelf-like flange plate 35 secured to the upstanding vertical bracket plate 20 subjacent the horizontal plane of the stop flanges 32, 32', as shown in Figure 4. The shelf flange 35 is thus adapted to support the stop bar 38 in a position wherein the transverse end edges 33, 33 of the stop flanges 32, 32' will engage the stop bar 38 and limit swinging move-

ment of the tubular boom member 27. Thus, the tubular boom member may be locked against rotation and may be held in a substantially longitudinally extending position relative to the main plate member 12, to facilitate the transportation of the boom attachment and to prevent undesired swinging of the boom portion thereof.

It will be understood that the stop bar 38 is readily removable, since it is not secured in any way to the supporting shelf element 35. When so removed, the flange elements 32, 32 may swing freely toward the transverse upstanding bracket plate 20, for example, may rotate with the boom member 27 to the positions thereof shown in dotted view in Figure 5.

A pair of depending vertical gusset plates 38, 38 are rigidly secured between the bottom surface of the upper pivot lug 26 and the transversely extending upstanding bracket plate 20, said gusset plates being spaced symmetrically on opposite sides of the pivot pin member 31, as is clearly shown in Figure 5.

Designated at 39 is a second tubular boom member which is telescopically received in the first tubular boom member 27, the boom member 39 being provided with longitudinally spaced apertures 40 which are selectively registerable with apertures 41 provided on the first boom member 27, so that the second boom member 39 may be secured in an adjusted position relative to the first boom member 27 by means of suitable fastening pins or bolts extending through the registering apertures 40 and 41. Thus, the boom member 39 may be extended to a desired position relative to the boom member 27 and may be locked in this position by means of a fastening bolt engaged through the apertures 41 and selected apertures 40.

Designated generally at 42 is a load carrier assembly comprising a horizontal base plate 44 to which is secured a downwardly concave top cover plate 45, the top cover plate being braced relative to the base plate 44 by a pair of longitudinally extending spacer blocks 46, 46 welded between the bottom surface of the bowed upper plate 45 and the top surface of the horizontal lower plate 44. Rigidly secured centrally in the composite plate structure 43 defined by the aforesaid plates 44 and 45 is a vertical upstanding shaft member 47 which projects upwardly for a substantial distance and which is formed at its top portion with the regularly spaced, transversely extending apertures 48.

Rigidly secured to the end portion of the second tubular boom member 39 is a horizontally extending plate member 50 which is further braced to the end portion of the boom member 39 by a pair of offset side plates 51, 51 welded at their bottom edges to the horizontal plate member 50 and bolted at their inwardly offset end portions 53 to the opposite sides of the boom member 39.

The vertical shaft member 47 of the carrier assembly 42 extends through an aperture 54 provided in the horizontal plate member 50 and is rotatably supported on said plate member by a ball bearing assembly 55 which is mounted on the horizontal plate member 50 and which supports a collar member 56 adjustably secured to the vertical shaft member 47 by a horizontal, transversely extending fastening pin 57 extending through the collar member 56 and a selected aperture 48 in vertical shaft 47. As shown in Figure 6, the bearing assembly 55 includes a housing 58 which retains the components of the bearing assembly and which transmits the loading from collar 56 to the horizontal plate member 50 and thus to the boom member.

Designated at 60 is a horizontal capstan shaft journaled in upstanding lugs 61 secured on a side marginal portion of the composite plate structure 43 of the load carrier assembly 42. A ratchet disc 62 is provided on the capstan shaft 60, said disc being engaged by a pawl member 63 pivoted to the top plate 45 in the manner illustrated in Figure 7, engaging the ratchet 62 to prevent counterclockwise rotation of the capstan shaft 60, as viewed in Figure 7. Secured on the opposite marginal portion of

the top plate member 45 are a pair of upstanding pins 64, 64. Designated at 65, 65 are respective flexible strap members having the respective end portions 66, 66 which are engageable through longitudinal slots 67, 67 formed in the capstan shaft 60 on opposite sides of the ratchet disc 62, whereby the strap members 65, 65 may be attached to said capstan shaft. The strap members 65, 65 are provided on their opposite ends with the generally triangular ring members 68, 68 engageable on the upstanding pins 64, 64, whereby a load, such as a bundle of boards 69, illustrated in Figure 1, may be secured to the load carrier assembly 42 by tightening the strap member 65, namely, by rotating the capstan shaft 60 in a clockwise direction, as viewed in Figure 7.

The capstan shaft 60 is provided with squared opposite ends 70, 70, adapted to be engaged by a suitable wrench when it is desired to tighten the strap members 65, 65.

In using the attachment, the fork elements 15, 16 of 20 a fork lift truck 17 are engaged in the sleeve members 13 and 14, whereby the fork elements 15 and 16 connect the boom attachment to the fork lift truck. Thereafter, the truck 17 is moved to the location of the load, for example, the bundle 69 and the bundle is fastened to 25 the load carrier assembly 42 by engaging the strap members 65, 65 around the bundle and tightening the strap members in the manner above described, thus clamping the bundle to the underside of the plate 44 in the manner shown in Figure 6.

As shown in Figure 2, the stop bar 34 may be engaged 30 on its supporting shelf 35 under these conditions to allow the truck 17 to transport the bundle 69 to the box car, shown at 72, in which it is intended to place the load. When the load has been thus placed to a position adjacent the side of the box car, the fork elements 15, 16 35 may then be elevated to the necessary height to raise the load above the level of the floor of the freight car, and the stop bar 38 may be removed to allow the boom to swivel as required in order to align the bundle 69 with the door of the box car, which as above mentioned, may be relatively narrow, as in the case of a large number of presently available single-door box cars.

With the bundle 69 elevated, for example to the dotted view position shown in Figure 2, the bundle may be further rotated around the vertical axis defined by the carrier assembly shaft 47, to facilitate the entry of the bundle 45 into the narrow box car door. When the bundle has been properly aligned the bundle may be moved into the box 50 car by moving the truck 17 in a forward direction, sufficiently to completely place the bundle inside the box car. The bundle may then be lowered onto the box car floor, after which the strap members 65 may be released by disengaging the locking pawl 63 from the ratchet wheel 62. This allows the strap members to be unfastened and disengages the bundle 69 from the boom attachment. The attachment may then be withdrawn from the box car for further use.

While the use of the boom attachment above described 60 is especially adaptable in connection with loading material into single-door box cars wherein the doorways are relatively narrow, and wherein a maximum degree of maneuverability of the load is desirable, the attachment is also valuable for use in connection with loading conventional box cars of the double-door type wherein relatively wide doorways are provided.

While a specific embodiment of an improved boom attachment for a fork lift truck has been disclosed in the foregoing description, it will be understood that various modifications within the spirit of the invention may occur 70 to those skilled in the art. Therefore, it is intended that no limitations be placed on the invention except as defined by the scope of the appended claims.

What is claimed is:

1. A boom attachment for a fork lift truck comprising 75 a base having sleeve-like portions adapted to receive

the fork elements of a fork lift truck, upstanding bracket means on the rear end portion of said base, a horizontal first tubular boom member, means pivotally connecting the rear end portion of said boom member to said upstanding bracket means for rotation on a vertical axis, an outwardly projecting horizontal flange on each of the opposite sides of said first boom member extending adjacent said upstanding bracket means, removably mounted transversely extending bar means on said upstanding bracket means and being at times engageable by said flanges to limit rotation of said first boom member, a second boom member telescopically received in said first boom member, means adjustably securing said second boom member in said first boom member, and means on the forward end of said second boom member constructed and arranged to swivelly support a load carrier assembly for rotation on a vertical axis.

2. A boom attachment for a fork lift truck comprising a base having sleeve-like portions adapted to receive the fork elements of a fork lift truck, upstanding bracket means on the rear end portion of said base, a horizontal first tubular boom member, means pivotally connecting the rear end portion of said boom member to said upstanding bracket means for rotation on a vertical axis, an outwardly projecting horizontal flange on each of the opposite sides of said first boom member extending adjacent said upstanding bracket means, a transversely extending horizontal flange on said upstanding bracket means, a transverse horizontal stop bar removably mounted on said last-named flange and extending adjacent the rear edges of said first-named flanges and being engageable thereby to limit rotation of said first boom member, a second boom member telescopically received in said first boom member, means adjustably securing said second boom member in said first boom member, and means on the second boom member constructed and arranged to swivelly support a load carrier member for rotation on a vertical axis.

3. A boom attachment for a fork lift truck comprising a base having sleeve-like portions adapted to receive the fork elements of a fork lift truck, a transversely extending vertical bracket plate rigidly secured on the rear end portion of said base, a horizontal first tubular boom member, a plurality of vertically spaced pivot lugs projecting forwardly from said bracket plate, pivot lugs on the rear end portion of said first boom member supportingly engaged on said first-named pivot lugs, a vertical pivot pin extending through and pivotally connecting said pivot lugs for rotation on the first boom member around the vertical axis, outwardly projecting horizontal flanges on each of the opposite sides of said first boom member spaced between the pivot lugs thereof and extending rearwardly toward said vertical bracket plate, transversely extending bar means removably mounted on said bracket plate and being at times engageable by said flanges to limit rotation of said first boom member, a second boom member telescopically received in said first boom member, means adjustably securing said second boom member in said first boom member, and means on the forward end of said second boom member constructed and arranged to swivelly support a load carrier member for rotation on a vertical axis.

4. A boom attachment for a fork lift truck comprising a base having sleeve-like portions adapted to receive the fork elements of a fork lift truck, a transversely extending vertical bracket plate rigidly secured on the rear end portion of said base, a horizontal first tubular boom member, a plurality of vertically spaced pivot lugs projecting forwardly from said bracket plate, pivot lugs on the rear end portion of said first boom member supportingly

5

engaged on said first-named pivot lugs, a vertical pivot pin extending through and pivotally connecting said pivot lugs for rotation on the first boom member around the vertical axis, outwardly projecting horizontal flanges on the opposite sides of said first boom member spaced between the pivot lugs thereof and extending rearwardly toward said vertical bracket plate, a transversely extending horizontal flange on said bracket plate, a transverse stop bar removably mounted on said last-named flange and extending adjacent the rear edges of said first-named flanges and being engageable thereby to limit rotation of said first boom member, a second boom member telescopically received in said first boom member, means adjustably securing said second boom member in said first boom member, and means on the forward end of said second boom member constructed and arranged to swivelly support a load carrier member for rotation on a vertical axis.

5. A boom attachment for a fork lift truck comprising a base having sleeve-like portions adapted to receive the fork elements of a fork lift truck, a transversely extending vertical bracket plate rigidly secured on the rear end portion of said base, a horizontal first tubular boom member, a plurality of vertically spaced horizontal pivot lugs projecting forwardly from said bracket plate, horizontal pivot lugs on the rear end portion of said first boom member supportingly engaged on said first-named pivot lugs, a vertical pivot pin extending through and pivotally connecting said pivot lugs for rotation of the first boom member around a vertical axis, outwardly projecting horizontal flanges on the opposite sides of said first boom member spaced between the pivot lugs thereof and extending rearwardly toward said vertical bracket plate, a transversely extending horizontal flange on said bracket plate, a transverse stop bar removably mounted on said last-named flange and extending adjacent the rear edges of said first-named flanges and being engageable thereby to limit rotation of said first boom member, a second boom member telescopically received in said first boom member, means adjustably securing said second boom member in said first boom member, and means on the second boom member constructed and arranged to swivelly support a load carrier member for rotation on a vertical axis.

6. A boom attachment for a fork lift truck comprising a base having sleeve-like portions adapted to receive the fork elements of a fork lift truck, upstanding bracket means on the rear end portion of said base, a horizontal boom member, means pivotally connecting the rear end portion of said boom member to said upstanding bracket means for rotation on a vertical axis, an outwardly projecting horizontal flange on each of the opposite sides of said boom member extending adjacent said upstanding bracket means, removably mounted transversely extending bar means on said upstanding bracket means and being at times engageable by said flanges to limit rotation of said boom member, and means on the forward end of said boom member constructed and arranged to swivelly support a load carrier assembly for rotation on a vertical axis.
